DENTURE CLEANING UNIT

Melvin H. Boldt, Glenview, Ill., assignor to Schick Electric Inc., Lancaster, Pa., a corporation of Delaware

Filed July 7, 1967, Ser. No. 7,732

Term of patent 14 years

(Cl. D49—1)

FIG. 1

FIG.3

FIG.2

FIG.4

FIG.5

FIGURE 1 is a front perspective view of a dental cleaning unit showing my new design;

FIGURE 2 is a side elevation thereof; the opposite side is a mirror image of the side shown;

FIGURE 3 is a rear elevation thereof;

FIGURE 4 is a bottom plan view thereof; and

FIGURE 5 is a top plan view thereof.

The dominant features of my design reside in the portions shown in full lines.

I claim:

The ornamental design for a denture cleaning unit, substantially as shown and described.
